UNITED STATES PATENT OFFICE.

HOWARD H. RALSTON, OF NORWOOD, OHIO, ASSIGNOR TO THE BULLOCK ELECTRIC MANUFACTURING COMPANY, A CORPORATION OF OHIO.

DYNAMO-ELECTRIC MACHINE.

No. 893,370.

Specification of Letters Patent.

Patented July 14, 1908.

Application filed November 29, 1905. Serial No. 289,566.

To all whom it may concern:

Be it known that I, HOWARD H. RALSTON, citizen of the United States, residing at Norwood, in the county of Hamilton and State of Ohio, have invented certain new and useful Improvements in Dynamo-Electric Machines, of which the following is a full, clear, and exact specification.

My invention relates to dynamo-electric machines, and particularly to the supports for the brush forks.

It sometimes happens that the brush supports are not properly located relative to the commutator. For example one or more of the brush supports may not be properly located circumferentially of the commutator; that is, the brushes carried thereby may not be on the proper line of commutation, or one or more of the brush supports may be too near the end of the armature. As brush riggings are usually constructed there is no provision for adjusting the brush supports separately, and accordingly any mistakes or inaccuracies of workmanship may entail considerable waste in material or result in sparking at the brushes.

The object of my invention is to provide means whereby each brush support can be adjusted so that it will be properly located relative to the commutator and armature. With this end in view I so mount the brush supports that each can be adjusted axially or axially and laterally of the commutator.

More specifically considered my invention consists in providing adjustable eccentric mountings for the radially extending brush forks of a dynamo electric machine, whereby each brush support can be shifted to its proper position.

My invention still further consists in certain novel details of construction and combinations of elements described in the specification and set forth in the appended claims.

For a better understanding of my invention, reference is had to the accompanying drawings forming a part of this application, in which

Figure 1 is a sectional elevation of a portion of a dynamo-electric machine equipped with my invention; Fig. 2 is a partial elevation of the same, parts being broken away for the sake of clearness; Fig. 3 is an elevation of one form of the eccentric support for each of the brush forks; Fig. 4 is an end view of the same; Fig. 5 is an elevation of a por-

tion of a brush fork showing a modification of the adjustable support or mounting therefor; and Fig. 6 is the bottom view of the same.

Referring to the figures of the drawing, I have shown at 10 a shaft of a dynamo-electric machine, on which are mounted the armature 11 and commutator 12. The stationary field frame 13 is provided on the end adjacent the commutator with a groove 14, in which is held the brush yoke. In this case the brush yoke consists of an outer ring 15, an inner ring 16, and the connecting arms 17. All the parts so far described are well known and I claim no novelty therein.

The brush forks are mounted in the inner ring 16, there being as many forks as field-poles. In the usual construction, the positions of the brush forks are not separately adjustable, except in a radial direction. It sometimes happens however, as was stated before, that the brush forks are not properly located. If the brush forks are too near the end of the armature, the latter may engage the forks as it rotates, and if the holes or openings in the inner ring which receive the brush fork supports are not properly spaced, the brushes of one or more of the forks will not be properly located on the line of commutation, and hence considerable sparking will result. I overcome these difficulties by providing means for adjusting each fork separately both laterally and axially of the commutator.

Radial spindles or bolts 18 are mounted in the yoke at proper intervals to support the brush forks 19. In the preferred form of my invention, the spindles are provided with enlarged eccentric portions 20 on which the forks are mounted. The forks are clamped to the eccentric portions by means of the split collar 21 and bolt 22. Each spindle is provided at its inner end with a squared portion 23, to which a wrench may be applied for adjusting the spindle. The spindles are all carefully insulated from the ring in which they are mounted by insulating tubes 24 and insulating washers 25. The ordinary cross connectors, for connecting respectively, all the positive brushes and all the negative brushes are shown at 26. Strap conductors 27 join the spindles to the proper cross connectors 26.

It is seen that by turning any one of the spindles 18, the position of the brush fork

mounted thereon can be adjusted. If the brushes are not on the proper line of commutation, all that is necessary is to turn the spindle until the brush fork is moved laterally or tangentially a sufficient distance. The fork will also be moved longitudinally of the commutator, but the longitudinal movement is immaterial, under ordinary circumstances. If, however, one or more of the brush forks are too near the armature and it is desired to adjust the latter longitudinally, it will be necessary to adjust all the spindles the same amount and obtain the proper circumferential position by adjusting the brush yoke.

In Figs. 5 and 6, I have shown a slight modification of my invention. Instead of mounting the brush forks on eccentric spindles, I here mount the forks on adjustable eccentric bushings which surround the spindles. One of the supporting spindles is shown at 18^a. Surrounding each spindle is an eccentric split bushing 28. The bushing is provided at its lower end with a flange 29, notched at 30, in order that a wrench may be applied thereto for adjustment. It is seen that, by loosening the nut on the clamping bolt 22 in the lugs of the split collar 21, the brush yoke can be adjusted at will. After the adjustment, the nut should again be tightened to hold the fork in the proper position.

I aim in my claims to cover all modifications and changes which do not involve a departure from the spirit and scope of my invention.

What I claim as new and desire to secure by Letters Patent is:—

1. In a dynamo-electric machine, a commutator, a brush yoke comprising a ring adjustably mounted on the frame of the machine, a radial spindle or rod in said ring, a brush fork supported on said spindle or rod, and means operative to permit the fork to be adjusted from one parallel plane to another and to be adjusted within any one of such planes.

2. In a dynamo-electric machine, a commutator, a brush yoke adjustably mounted on the frame of the machine, a plurality of brush forks mounted on said yoke, and

means operative to permit the forks to be adjusted relative to the yoke laterally and axially of the commutator.

3. In a dynamo-electric machine, a commutator, a plurality of brush forks, a plurality of brushes carried by each fork, and an eccentric supporting member for each fork, said members being separately adjustable.

4. In a dynamo-electric machine, a commutator, a brush yoke, a plurality of brush forks, and means for eccentrically mounting said brush forks on said brush yoke.

5. In a dynamo-electric machine, a brush yoke, a plurality of adjustable eccentric brush fork supports carried thereby, and a brush fork on each of said supports.

6. In a dynamo-electric machine, a brush yoke, a plurality of adjustable radial members having eccentric portions, and a brush fork supported on each of said eccentric portions.

7. In a dynamo-electric machine, a brush yoke comprising a ring, a plurality of eccentric spindles carried by said yoke, and a brush fork mounted on each of said spindles.

8. In a dynamo-electric machine, a brush yoke comprising a ring, a plurality of spindles mounted in said yoke, each of said spindles having an eccentric portion, and a brush fork mounted on the eccentric portion of each of said spindles.

9. In a dynamo-electric machine, a brush yoke, a plurality of spindles mounted therein, each of said spindles having an eccentric portion, a brush fork mounted on each eccentric spindle, and means for adjusting the position of each of said spindles to adjust the position of each brush fork.

10. In a dynamo-electric machine, a brush yoke comprising an outer ring, an inner ring, and a plurality of arms joining said rings, a plurality of spaced radial eccentric spindles mounted in said inner ring, a brush fork on each eccentric spindle, and means for separately adjusting each spindle.

In testimony whereof I affix my signature, in the presence of two witnesses.

HOWARD H. RALSTON.
